(57) **CLAIM**

The ornamental design for a clamp with replaceable nut, as shown and described.

DESCRIPTION

FIG. 1 is a front perspective view of the clamp with replaceable nut of the present design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a front perspective exploded view thereof.

The broken lines that represent a bolt and portions of the clamp form no part of the claimed design.
